FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The difference in the shading between the stick of the pet treat and the three chunks of the pet treat are used to best describe the specific shapes of those portions and do not represent a contrast in appearance. The broken lines in FIGS.

1 and 4–7 illustrate portions of the pet treat that form no part of the claimed design.
